UNITED STATES PATENT OFFICE.

JOHN W. HENSON, OF NEW YORK, N. Y.

DESIGN FOR FABRIC.

SPECIFICATION forming part of Design No. 36,791, dated February 9, 1904.

Application filed January 13, 1904. Serial No. 188,928. Term of patent 3½ years.

To all whom it may concern:

Be it known that I, JOHN W. HENSON, a subject of the King of Great Britain, and a resident of the city of New York, borough of Manhattan, in the county and State of New York, have invented a new, original, and ornamental Design for a Fabric, reference being had to the accompanying drawing, in which the figure is a plan view of a fabric showing the design.

I claim as new and desire to secure by Letters Patent—

The ornamental design for a fabric, herein shown.

In testimony whereof I have signed my name to this specification in the presence of two subscribing witnesses.

JOHN W. HENSON.
